UNITED STATES PATENT OFFICE

2,274,433

RANGE CONSTRUCTION

Arthur P. Schulz, Michigan City, Ind., assignor
to G. & J. Teller, Chicago, Ill., a partnership
composed of Grace Teller and Jacob Teller

Application April 12, 1938, Serial No. 201,609

2 Claims. (Cl. 126—39)

This invention relates to a range construction. More particularly, the invention relates to a gas range construction embodying a tubular frame, a cooking top unit removably and directly supported by the frame, and a baking and broiling unit detachably supported by the frame in either a high or low position with respect thereto.

A primary object of the invention is the provision of a range construction embodying a unitary tubular frame, and separate cooking top and making units constructed and associated with the frame in such manner that they may readily be placed in different positions with respect to the frame and to each other.

A further object of the invention is the provision of a range construction embodying a unitary tubular frame, a separate cooking top unit directly and removably supported by the frame, and a combined baking and broiling unit so constructed and associated with the frame whereby it may readily be supported by the frame in a high position providing a console or alternately in a low position providing a table top co-planular with the top of the cooking top unit.

A still further object of the invention is the provision of a range construction of the character above noted wherein the tubular frame serves in part as a gas carrying conduit and wherein simple means are provided for supplying gas to both the baking and broiler burners when the combined baking and broiling unit is in either the high or low position.

A still further object of the invention is the provision of a range which is relatively simple in construction, presents a pleasing appearance, is rigid in any of the interchangeable positions of its parts, and which is capable of manufacture at relatively low cost.

With the above objects in view as well as others which will present themselves in the course of the following disclosure, reference will be made to the accompanying drawings, forming part of same, and wherein—

Figure 1 is a perspective view of a preferred embodiment of the improved range construction, the combined baking and broiling unit being illustrated in high or console position by full lines and in alternative low or table top position in dot and dash lines.

Fig. 2 is a perspective view illustrating the various parts of the range construction in separated position.

Fig. 3 is a more or less diagrammatic vertical sectional view illustrating in particular the means

for mounting the combined baking and broiling unit in high or low positions.

Fig. 4 is an end elevation partly broken away and in section showing the relation between the cooking top and combined baking and broiling units in the high position of the latter.

Fig. 5 is a detail vertical sectional view illustrating the operative relation between the gas manifold and one of the cooking top unit mixers.

Fig. 6 is a vertical sectional view of the combined baking and broiling unit disclosing a preferred means for supplying gas to the baking burner when the unit is in either high or low position.

Fig. 6a is a fragmental view similar to Fig. 6 but disclosing a preferred means for supplying gas to the broiler burner when the combined baking and broiling unit is in either high or low position.

Fig. 7 is a perspective view of a modification of the invention.

Fig. 8 is a perspective view of a still further modification.

Referring to the drawings, wherein like reference characters designate like parts, and referring first to Figs. 1 to 6A inclusive, F designates the supporting frame in its entirety. This frame is preferably constructed from tubular stock and comprises a single length of tubing providing a pair of vertical end uprights 10 interconnected at the top by a transverse member 11 and at the bottom or lower ends, these uprights continue at right angles to provide a pair of longitudinal members 12. The uprights 10 are preferably interconnected adjacent their lower ends by a transverse strut 13 and suitably formed supporting feet 14 are secured to members 12 adjacent the uprights 10.

The longitudinal members 12 are suitably connected at their ends to the vertical members 15 of a second single length of tubing which vertical members are interconnected at their lower ends by a transverse foot member 16 and which at their upper ends are extended in the form of horizontal members 17 which are parallel with members 12 and in horizontal alignment with the transverse member 11. The vertical members 15 are also preferably connected by a transverse strut 18 adjacent their junction with the horizontal members 17.

This provides a frame which is strong as well as attractive in appearance and one which is particularly adapted to removably support a combined baking and broiler unit as well as a cooking top unit with provision for high and low

positions of the combined baking and broiler unit resulting in a console or table top type of range. It will be particularly noted from Fig. 2 that the horizontal members 17 terminate short of the transverse member 11 thereby providing an open space in the frame and which is adapted to receive the oven O in a manner about to be described.

The horizontal members 17 are each provided with a fixed collar 19 adjacent the free end thereof for providing a pair of oven socket engaging pins 21.

The transverse member 11 is provided with a pair of short pins or dowels 22 in longitudinal alignment with the pins 21.

The oven O at the right hand side thereof is provided with two pairs of sockets 23 and 24 and is provided at the left hand side thereof with shallow sockets 25 and 26 longitudinally aligned with the sockets 23 and 24. This construction provides for positioning the oven O in two different vertical positions as is illustrated in full and dotted lines in Fig. 1.

When the oven or combined baking and broiling unit is in a high or console position as illustrated, the pins 21 are engaged within the sockets 23 and the pins 22 are engaged in the sockets 25. The collars 19 provide stops to limit movement of the unit O horizontally to the right of the frame F.

When it is desired to place the combined baking and broiling unit O in a low position as illustrated by dot-and-dash lines in Fig. 1, the uprights 10 are flexed outwardly thus withdrawing pins 22 from the sockets 25 whereupon the unit O is free to be tipped upwardly at the left end and then drawn outwardly from the pins 21. The unit O may then be placed in the low position preferably from below the frame by first entering pins 21 in sockets 24 and then pushing the left end of the unit upwardly while at the same time flexing uprights 10 to thereby enter the pins 22 in the sockets 26.

The right hand end of the tubular frame F is preferably utilized to convey the gas to the unit O as well as to the cooking top unit C.

In this adaptation the rear vertical member 15 is provided with a gas connection 30 which preferably precludes the flow of gas upwardly in this member.

The gas flows from the connection 30 through members 16 and 15 as well as the front horizontal member 17 which by suitable means is closed within the adjacent pin 21.

The front horizontal member 17 therefore functions as a gas manifold and is provided with valves 31 for the cooking top burners 32, a valve 33 for controlling the flow of gas to the baking burner 34 and a valve 33' for controlling the flow of gas to the broiled burner 35.

The cooking top unit C embodies a rectangular frame having arcuate ledges 36 and 37 at its front and rear edges respectively which conform to and detachably seat upon the horizontal members 17.

When the unit C is in position the valves 31 align with the mixing tubes 38 of the burners 32 as is clearly indicated in Fig. 5.

A suitable convexed door 39 hinged at its lower edge at 40 is provided for normally concealing the valves 31 and 33.

A splasher back S is provided and which is detachably secured in operative position by any suitable means.

While various means may be provided for ef-

fecting flow of gas to the burners 34 and 35 when the combined baking and broiling unit is in either a high or low position, a preferred arrangement for the respective burners is illustrated in Figs. 6 and 6A. As indicated in Fig. 6 three vertical pipes 41, 42 and 43 are disposed within or adjacent the right hand wall of the unit O. The pipe 41 communicates at opposite ends with detachable connectors 44 for alternative connection with a short pipe 45 communicating with the valve 33.

The pipe 42 is in communication with pipe 41 at its lower end and at its upper end communicates with a chamber or thermostat 46. The pipe 43 interconnects the chamber 45 and burner 34.

The broiler burner 35 is connected in substantially the same way as the baking burner 34, the corresponding vertical pipes being indicated in Fig. 6—A, at 41', 42' and 43', the latter pipe being connected with the burner 35 by the horizontal pipe 47.

The connectors 44' are adapted for alternate connection with valves 33'.

It is of course to be understood that the piping individual to the two burners are disposed in offset relation but sufficiently close to permit ready connection with the aligned valves 33 and 33'.

Thus it will be seen that by this arrangement gas will be supplied to the burners 34 and 35 in either alternate position of the unit O.

In Fig. 7 is illustrated a modified form of the invention wherein the frame F' is provided with a low shelf 50 upon which rests the bottom of an oven O' and which at its top is provided with arcuate ledges 51 similar to the ledges 36 and 37 on the cooking top unit C.

In this form of the invention two two-burner cooking top units C' are provided with one disposed upon each side of the oven unit O', the cooking top units C' being supported by the frame in the same manner as the unit C. This range construction also includes a splasher back S' detachably secured in position in any desired manner.

According to the form of invention disclosed in Fig. 8 only one cooking top unit C'' of four burner capacity is provided and the oven unit O'' and unit C'' are disposed adjacent opposite ends at the frame F''.

Thus by providing the oven and cooking top units with the frame engaging arcuate ledges various relative arrangements of the units are provided. Gas may be supplied through the frames F' and F'' or by any other desired means to the burners in the oven and cooking top units.

While I have disclosed only certain specific embodiments of my invention, same are to be considered as illustrative only, and not restrictive, the scope of the invention being defined in the subjoined claims.

What I claim and desire to secure by U. S. Letters Patent is:

1. A gas range construction comprising a unitary tubular frame embodying a pair of vertical members at each end thereof, a horizontal member interconnecting the upper ends of one pair of vertical members, a pair of horizontal members in continuation of the other pair of vertical members, the pair of horizontal members being parallel and extending longitudinally of the frame toward and in horizontal alignment with the first horizontal member and with the free ends thereof in spaced relation to the first

horizontal member, horizontal spaced pins on the first horizontal member and alined with said horizontal members, and a combined baking and broiling unit having sockets in opposite sides thereof respectively receiving the free ends of the pair of horizontal members and the pins for holding the combined baking and broiling unit in operative position.

2. In a gas stove, a frame including a pair of upper parallel members extending from one end of said frame toward the other end thereof and terminating in spaced relation thereto, said frame having a cross member at its other end in the plane of said parallel members and having pins projecting therefrom in alinement with said

parallel members, an oven having vertically spaced parallel sockets extending from one side thereof into the oven and adapted to receive the ends of said parallel members, said frame also having vertically spaced sockets opposite the first mentioned sockets for receiving said pins, top and bottom burners in said oven, gas supply means connecting said burners and having vertically spaced connecting means external of the oven and located at equal distances below the respective first sockets, and a valved gas connection carried by one of said parallel members and adapted for connection selectively to said connecting means.

ARTHUR P. SCHULZ.
